COMBINED CHARGER AND HOLDER FOR AN ELECTRIC WET SHAVER

Bruce F. Ray, Danvers, Mass., assignor to The Gillette Company, Boston, Mass., a corporation of Delaware

Filed Dec. 18, 1969, Ser. No. 20,566

Term of patent 14 years

Int. Cl. D13—02

U.S. Cl. D26—15

Fig. 1.

Fig. 5.

Fig. 6.

Fig. 2.

Fig. 3.

Fig. 4.

FIG. 1 is a perspective view of a combined charger and holder for an electric wet shaver showing my new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a bottom plan view thereof.

The undisclosed side is substantially the same in appearance as the side shown.

I claim:

The ornamental design for a combined charger and holder for an electric wet shaver, substantially as shown and described.
